UNITED STATES PATENT OFFICE.

HARVEY F. MARANVILLE, OF AKRON, OHIO.

VENTILATOR.

1,328,094.

Specification of Letters Patent. Patented Jan. 13, 1920.

Application filed May 25, 1916, Serial No. 99,722. Renewed October 6, 1919. Serial No. 328,925.

To all whom it may concern:

Be it known that I, HARVEY F. MARANVILLE, a citizen of the United States, residing at Akron, in the county of Summit and State of Ohio, have invented a certain new and useful Improvement in Ventilators, of which the following is a full, clear, and exact description, reference being had to the accompanying drawings.

10 This invention relates to ventilators and more particularly to ventilators of the rotary cowl type which are adapted to discharge the exhausted air in a direction opposite to that from which the wind may be blowing at any time. The general objects of my invention are the provision of a ventilator of this type which will provide a maximum aspirating effect with a corresponding maximum exhausting capacity; 20 the provision of a device of this type of the maximum simplicity of construction and one in which the entrance of rain or snow into the air building shall be impossible; while additional objects and advantages will appear as the description proceeds.

Generally speaking my invention may be defined as consisting of the combinations and constructions recited in the claims here-to annexed and illustrated in one embodiment in the drawings accompanying and forming a part hereof, wherein Figure 1 is a vertical sectional view through a ventilator constructed in accordance with my invention; Fig. 2 is a transverse sectional view 30 taken upon the line 2—2 of Fig. 1 and looking downwardly; Fig. 3 represents a front elevation of my improved ventilator; and Fig. 4 represents a side elevation of the complete ventilator.

40 Describing the parts by reference characters, 1 denotes a base member or roof fitting such as is usually employed with buildings for ventilating purposes. It is cylindrical in shape and is secured to the roof in any 45 suitable or desirable manner. Pivottally secured above the open upper end of this base member is my improved cowl which is here shown as having a top plate 2, bottom plate 3, side plates 4—4, shield 5, and vane 6. 50 The bottom plate 3 is formed with a circular aperture 7 loosely receiving the projecting upper end of the base 1, and the sides 4—4 are spaced one on each side of this aperture as shown in Fig. 2, the portions of said sides 55 adjacent the rear of the cowl preferably converging somewhat as shown at 8—8 to form

a mouth 9, whose vertical lips are preferably flared sidewise as shown at 10—10. The shield 5 is made of semi-circular shape and is secured in vertical position above the 60 plate 3 so as to traverse the mouth 9 immediately at the edge of the opening 7 with its free edges 12—12 spaced from the portions 8—8 so as to provide elongated passageways 13—13, arranged one at each side of the 65 opening 7. The top member 2 is secured to the sides 4—4 and to the top of the shield 5 so as to produce a very rigid arrangement. The lips 12—12 of the shield are preferably arranged substantially abreast of the center 70 of the opening 7, since at this point the rush of air through the openings 13—13 produces a maximum of suction upon the air column. If these lips are projected farther toward the discharge mouth of the cowl the suction 75 is decreased, while if terminated short of this point, rain and snow can find their way into the air shaft.

The top member 2 preferably overhangs the bottom member 3 at the discharge mouth 80 of the cowl, so as to prevent rain and snow from beating into the air shaft, and also to guard against the ingress of any down draft such as frequently occurs in the neighborhood of high buildings. The entrance of 85 rain and snow is also minimized by the extension of the base member 1 above the bottom member 3. The lips of the discharge mouth are preferably turned laterally as shown at 15—15, which taken with the 90 inclination of the side walls at this point, causes the air which passes outside the ventilator to be thrown outward and also upward.

Any suitable or convenient arrangement 95 can be employed for supporting the cowl in operative position. The simplest which I have conceived comprises a bridge member 20 traversing the upper end of the base member 1 and carrying a socket 21 of some 100 nature, a vertical pivot shaft 22 carried by the top plate 2 and steadied by a cross piece 23, said shaft having a pivot head engaging the socket 21, and a suitable bracing arrangement carried by the base 1 and engaging said shaft near its upper end, such 105 for example as the metal strips 24—24 shown in the drawings.

With this arrangement I secure a maximum of aspirating action, without any possible eddying or swirling of rain or snow into the air shaft, the air passing through

the passageways 13—13 serving to overcome the inward eddying effect which is observed when no interior air passages are provided.

5 While I have described my invention in detail it will be obvious that many changes in construction could be made without departing from the scope of my invention, wherefore I do not limit myself except as 10 described in the claims hereto annexed or required by the prior state of the art.

Having thus described my invention, what I claim is:

15 1. A rotary cowl for ventilators comprising a pair of upright side walls and a top member, said side walls terminating at open inlet and outlet mouths arranged at opposite sides of said cowl and being tapered inwardly toward said inlet mouth beginning at a point substantially abreast of the pivot axis, and a concave shield depending from said top member within said inlet mouth, said shield having its convex face

turned toward said mouth and having its free edges extending to points substantially 25 abreast of the pivot axis and spaced from said side walls to define narrow passageways.

2. A rotary cowl for ventilators comprising a pair of upright side walls and a top member, said side walls terminating at open 30 inlet and outlet mouths arranged at opposite sides of said cowl and being tapered inwardly toward said inlet mouth beginning at a point substantially abreast of the pivot axis, both inlet and outlet mouths being formed with flaring lips, and a concave shield depending from said top member within said inlet mouth, said shield having its convex face 35 turned toward said mouth and having its free edges extending to points substantially abreast of the pivot axis and spaced from said side walls to define narrow passageways.

In testimony whereof, I hereunto affix my signature.

HARVEY F. MARANVILLE.
